DESIGN FOR A SPRAY GUN

Svend Bramsen and Fred W. Wahlin, Chicago,
Ill., assignors to Binks Manufacturing Company,
Chicago, Ill., a corporation of Delaware

Application February 28, 1936, Serial No. 61,414

Term of patent 7 years

To all whom it may concern:

Be it known that we, Svend Bramsen and Fred W. Wahlin, both citizens of the United States, and both residing at Chicago, Illinois, have invented a new, original, and ornamental Design for a Spray Gun, of which the following is a specification, reference being had to the accompanying drawing, forming part thereof.

In the drawing,

Fig. 1 is a side elevation of a spray gun, showing our new design.

Fig. 2 is a rear elevation of the same.

Fig. 3 is a plan view of the same.

We claim:

The ornamental design for a spray gun, substantially as shown.

SVEND BRAMSEN.
